J. PONDELICK

PISTON FOR INTERNAL COMBUSTION ENGINES

Filed March 11, 1925

Inventor

John Pondelick

UNITED STATES PATENT OFFICE.

JOHN PONDELICK, OF RIVERSIDE, ILLINOIS.

PISTON FOR INTERNAL-COMBUSTION ENGINES.

Application filed March 11, 1925. Serial No. 14,590.

To all whom it may concern:

Be it known that I, JOHN PONDELICK, a citizen of the United States, and a resident of Riverside, county of Cook, Illinois, have 5 invented certain new and useful Improvements in and for Pistons for Internal-Combustion Engines, of which the following is a specification.

This invention relates to pistons for internal combustion engines, and more particularly to pistons composed of aluminum or an aluminum alloy, and has for its main object to provide wearing surfaces for such pistons.

10 It is well known that aluminum and aluminum alloys are too soft and generally of insufficiently uniform density to be well adapted for the manufacture of pistons for internal combustion engines unless equipped with 15 wearing surfaces of a metal, preferably cast iron, which is well adapted to stand the wear and, by reason of the fact that cylinders of such engines are most generally made of cast-iron, have the same coefficient of expansion as said cylinders.

The object of the present invention is, therefore to provide a composite piston consisting of a body of aluminum or an aluminum alloy and certain annular cast-iron 20 wearing elements permanently associated with the aluminum or similar body in such manner as to permit free relative contraction and expansion of said wearing elements and said body without, however, permitting 25 or occasioning any looseness in the association of said parts such as might occasion leakage or rattling during piston reciprocations.

A further object of the invention is to so 30 effect association of said body and wearing elements as to obviate chipping or breakage of the latter under the influence of the strains and stresses resulting from the difference in coefficients of expansion thereof.

40 A further object of the invention is to so construct or form the wearing elements as to cause the metal of the body of the piston when cast about the said elements, to flow into every crevice or hollow of the latter to thereby effect uniformity of association of said body and said elements.

A further object of the invention is to so 45 form the wearing elements as to avoid delicate or easily fracturable parts or projections for locking the same to the piston body and to make them of such length (ax-

ially of the piston) and proportionate thinness as to permit the same to yield to extreme stresses due to overheating of the engine cylinders and the like without fracturing.

The preferred embodiment of the invention is illustrated in the accompanying drawings, wherein:

Fig. 1 is a central longitudinal of a piston 65 constructed in accordance with the invention.

Fig. 2 is a plan view of a reinforcing member for the piston, constructed in accordance 70 with the invention.

Figs. 3, 4 and 5 are radial sections on the lines 3—3, 4—4 and 5—5, respectively, of Fig. 2.

The piston, which is of the usual trunk type used in internal combustion engines, 75 consists of the cylindrical body 1 provided with an integral head 2 at one end and with bearings 3 between its ends for the shaft or pin of the connecting rod (not shown).

The inner projecting ends of said bearings 3 are reinforced and supported by the integral radial ribs 4 extending in tapered form from the head 2 to said bearings. The piston is provided just below the head 2 and above the bearings 3 with a plurality 80 of annular grooves 5 adapted to receive ordinary piston rings.

Between said bearings 3 and the nearest adjacent groove 5, and between the bearings 90 and the open end of the piston, there are cast into the same the wearing elements 6 and 7 respectively, the former being illustrated in detail in Figs. 2, 3 and 4 and the element 7 being of substantially identical construction but of different dimensions 95 than the element 6.

The elements 6 and 7 are substantially identical in construction but may differ as to length (axially of the piston). Hence a description of one thereof will apply to 100 both except as hereinafter particularly pointed out.

Each of said elements 6 and 7 is composed, 105 preferably, of cast iron and comprises a ring having a somewhat spheroid-concave inner surface 8 bordered by the annular flanges 9 having opposed concavely rounded, opposed surfaces which merge into the substantially spheroid-concave inner face of the ring. Or, in other words, the radius of curvature (axially of the ring) of the inner surface of 110 the ring is reduced to provide fillets where

said surface merges into the inner surfaces of said flanges 9. This permits the molten aluminum to readily flow into and fill every part of the hollow presented by the inner 5 surface of the ring.

The end surfaces of the ring are parallel over that portion of their areas indicated at 10 lying next adjacent the outer surface of the same. The portions of said end 10 surfaces or faces lying inwardly of the portions or areas 10 are divided into an equal number of relatively oppositely tapered or beveled areas 11 and 12, respectively, the areas 11 at one end of the ring being opposed to the areas 11 of the other end, this being true also of the areas 12. Thus radial sections of the ring through an arcuate area 11 will, as shown in Fig. 4, present end surfaces which converge toward the axis of 15 the ring while similar sections through the areas 12 will, as shown in Fig. 5, present surfaces which diverge toward the ring axis. Between the areas 11 and 12, there are formed the rounded shoulders 13 which, by 20 engagement with the similar shoulders formed in the body of the piston, prevent rotation of the rings relatively to the said body without, however, interfering with the relative expansion and contraction of the 25 latter relatively to the rings 6 and 7. The parallel faces of the annular grooves 8 also permit such relative expansion and contraction.

Preferably only the ring 6 is provided 30 at diametrically opposite points with the inwardly extending projections 13 which engage at their extreme inner end portions in the ribs 4 if the latter are provided.

In casting the rings 6 and 7, the outer 40 body portions lying between the parallel end faces 11 thereof, are rendered wide enough radially to provide excess metal for greater strength and rigidity in accurately machining the inner and end faces thereof and also to permit the rings to be readily 45 supported in the mold into which the aluminum body-metal is cast, the initial diameter of the latter being less than the extreme diameter of the said rings. Preferably the outer surface of the ring is machined before the same is mounted in the mold to cut 50 away some of the excess metal and leave the two annular flanges 15. These are afterwards cut off as the outer surface of the ring 55 is turned down to the diameter indicated by the dotted lines 16.

Obviously the rings 6 and 7 will act similarly to chills in castiron molds and will 60 cause a more rapid congealation of the aluminum immediately proximate thereto. Furthermore, the coefficient of expansion of the aluminum is greater than that of castiron so that in cooling, the aluminum will shrink 65 away from the ring surfaces both radially and longitudinally of the piston. During

this shrinkage, the aluminum surfaces opposed to the surfaces 12 of the rings will move into snug contact with the latter and thus avoid all loose association between the rings and the piston body. Upon expansion 70 of the latter, both radially and longitudinally under the influence of engine-cylinder heat, the aluminum surfaces opposed to the ring-surfaces 11 will move into snug contact with the latter and thereby again maintain the rigid association of the rings and piston body. 75

After removal from the mold, the piston body is turned down in a lathe to a diameter sufficiently less than that of the cylinder for 80 which it is intended to prevent it from too snugly fitting the latter upon expansion under running conditions. The exposed portions of the rings are then turned down to a diameter providing the usual running fit 85 within the engine cylinder.

The portions of the ring ends presenting the tapered surfaces 12 constitute arcuate flanges which possess great strength and are not easily broken away from the ring body. The cross-sectional dimensions of the latter are also so proportioned to length axially of and to diameter of the ring as to render it sufficiently flexible to accommodate itself to unusual strains and stresses 90 of an unequal or unbalanced nature which might result from differences in temperature at opposite sides of the piston or cylinder or both or which may result from differences in density of the metal or cross-sectional dimensions of the cylinder body. 95

The body-metal which fills the hollow in the inner face of the ring will, when fully shrunk, be spaced from said face only to a very inappreciable extent. The latter may 100 be defined as being within the limits of flexibility of the ring and thus affording opposed reinforcing elements which will prevent flexion of said rings to the point where there is danger of fracture thereof. 110

I claim as my invention:

1. In a composite piston of the kind specified, wearing elements having end surface formations relatively arranged to constitute alternately oppositely disposed wedge formations. 115

2. In a composite piston of the kind specified, wearing elements having end surface formations presenting alternately oppositely disposed obstructions for engagement by the opposed similar surfaces of the body-metal during expansion and contraction respectively of the piston body. 120

3. In a composite piston of the kind specified, wearing elements provided in their inner peripheral faces with annular substantially spherò-concave grooves merging into parallel annular edge-flanges for permitting free relative expansion and contraction of said elements and the piston body without 125 130

imparting strains or stresses upon the walls of said grooves while effecting the projection into said grooves of a wide rib of interfitting metal for preventing excessive flexion 5 of said elements.

4. In a composite piston of the kind specified, wearing elements provided in their inner peripheral faces with annular substantially spheroid-concave grooves merging into 10 parallel annular edge-flanges for permitting free relative expansion and contraction of said elements and the piston body without imparting strains or stresses upon the walls of said grooves, the end surfaces of said elements being divided into a plurality of alternately oppositely beveled arcuate portions 15 to effect a wedging engagement with the body metal upon a relative movement of said wearing elements and piston body in response to variations in temperature of the 20 entire structure.

5. In a composite piston of the kind specified, wearing elements provided in their inner faces with substantially spheroid-concave 25 annular grooves merging into annular edge-flanges, and alternately oppositely disposed bevel formations at the ends of said wearing elements for effecting a wedging engagement with the body metal upon a relative movement of said wearing elements and piston body in response to variations in temperature of the whole structure.

6. In a composite piston of the kind specified, wearing elements having end surfaces 30 in part annularly parallel and in part oppositely beveled, the beveled portions adapted to effect a wedging engagement with the body metal upon a relative movement of

said wearing elements and piston body in response to variations in temperature of the 40 whole structure.

7. In a composite piston of the kind specified, wearing elements having end surfaces in part annularly parallel and in part alternately beveled to constitute alternately 45 oppositely disposed wedge formations for effecting a wedging engagement with the body metal upon a relative movement of said wearing elements and piston body in response to variations in temperature of the 50 whole structure.

8. In a composite piston of the kind specified, wearing elements provided in their inner peripheral faces with substantially 55 spheroid-concave annular grooves, the end surfaces of said elements presenting in part annular parallel areas and in part oppositely beveled portions, the latter adapted to effect a wedging engagement with the body metal upon a relative movement of said wearing 60 elements and piston body in response to variations in temperature of the whole structure.

9. In a composite piston of the kind specified, wearing elements provided in their inner peripheral faces with substantially spheroid-concave annular grooves, the end surfaces of said elements presenting in part annular parallel areas and in part alternately oppositely beveled portions, the latter 65 adapted to effect a wedging engagement with the body metal upon a relative movement of said wearing elements and piston body in response to variations in temperature of the 70 whole structure.

JOHN PONDELICK.
